STRETCHER INSERT FOR THE BASE OF A FILE RACK

William Chovanec, Montvale, N.J., assignor to Art Steel Company, Inc., Bronx, N.Y.

Filed Apr. 27, 1971, Ser. No. 138,007

Term of patent 14 years

Int. Cl. D6—06

U.S. Cl. D6—191

FIG. 1

FIG. 2

FIG. 3

FIG. 4

FIG. 5

FIG. 6

FIG. 7

FIG. 1 is a top plan view of a stretcher insert for the base of a file rack embodying by new design.

FIG. 2 is a side elevational view thereof;

FIG. 3 is a bottom plan view thereof;

FIG. 4 is an end view thereof;

FIG. 5 is a cross-sectional view taken on line 5—5 of FIG. 1; and

FIG. 6 is a cross-sectional view taken on line 6—6 of FIG. 1; and

FIG. 7 is a cross-sectional view taken on line 7—7 of FIG. 3.

I claim:

The ornamental design for a stretcher insert for the base of a file rack, substantially as shown.
